Inventor
Michael Redlinger

Attorney
Thomas B. Lyle

UNITED STATES PATENT OFFICE.

MICHAEL REDLINGER, OF PORTLAND, OREGON.

VIOLIN.

Application filed October 20, 1925. Serial No. 63,655.

It has been heretofore proposed to increase the quality and strength of the tone of stringed instruments and particularly of the violin by providing a base bar longitudinally of the stringed instrument, the same being placed on the under side of the top wall structure, the same being applied longitudinally of the instrument and beneath one of the strings of the instrument; but, in so far as I am advised no attempt has been made to provide means in connection with the base bar, wherein the required tension may be secured upon the base bar. This, I have provided in my present application for patent.

A further object of my invention, consists in providing a base bar having disposed at either end thereof, an enlarged sectional area which is adapted to attachment to the under side of the top wall surface, and which bridges the space therebetween and it is adapted to the placement of a movable support between the top wall structure and the base bar so as to increase, or decrease, the tension upon the base bar and, therefore, upon the top wall structure as well.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:—

Fig. 1 is an inverted plan view, of my new and improved violin, illustrating my new and improved base bar, in position, on the under side of the top wall surface of the violin.

Fig. 2 is a longitudinal, cross section view, taken on line 2—2 of Fig. 1, looking in the direction indicated.

Fig. 3 is a cross section view, taken on line 3—3 of Fig. 1, looking in the direction indicated.

Fig. 4 is an inverted perspective view of the base bar, illustrating a preferred form of attaching the same to the under side of the top wall of the stringed instrument and illustrating the tension member as applied thereto.

Like reference characters refer to like parts throughout the several views.

1 is the body portion of the stringed instrument, having a top wall surface 2, dis-

posed upon the body portion,—the bridge of the violin being shown at 3, and the bridge post at 4. Disposed longitudinally of the instrument and on the under side of the top wall surface is the base bar 5, which is positioned beneath one of the strings of the instrument and longitudinally of the instrument, and has enlarged end terminals 6 and 7, disposed at either end of the same; base bar 5, is made integral therewith. These end terminals 6 and 7, are so made in contour and arrangement to be readily attached to the underside of the top wall surface 2 by glue, or other suitable fastening means. In a preferred embodiment of my new and improved violin, the base bar is attached to the underside of the top wall surface by means of the end terminals and that portion of the bar intermediate its ends is spaced apart from the under surface of the top wall 2. Disposed between the end terminals and the base bar 5, is a secondary bar 8, the same being secured to the under side of the top wall of the stringed instrument and in line with the base bar. The secondary bar is directly mounted to the undersurface of the top wall and in parallel alignment with the base bar and in spaced relationship therewith. The adjacent or oppositely positioned edges of the base bar 5 and the secondary bar 8 are curved longitudinally, but are not of the same degree of curvature, the secondary bar being slightly more curved than the base bar, so that the distance between the two bars varies intermediate their ends. The distance between the bars being the shortest at the longitudinal center points of each of the bars, which center points are spaced opposite each other. The tensioning post 9 has grooved ends which fit over and engage the oppositely facing curved surfaces of the two bars, and as the tension bar is moved along the bars toward the center thereof, the pressure upon the tension bar increases, and it is the change of pressure upon the two bars that modifies or changes the tone of the instrument.

Experience has shown that the tension placed upon the base bar determines the quality of the tones to be produced upon the stringed instrument and that this quality of tone and the volume may be determined and increased, or diminished, by the change in position of the tensioning member, which

increases, or decreases, the tension upon the base bar and therefore, upon the top wall of the instrument. Because of the fact that my new and improved violin has the base bar with its tensioning member placed on the inner side of the top wall, does not in any way detract from the beauty of the instrument. The same may be attached at the time of the manufacture of the instrument, or placed at a later time.

One of the primary objects of my invention is to compensate for the changes in tension of the top wall surface of the stringed instrument caused by changes in temperature, climatic changes and other natural causes. My invention also enables those skilled in such matters to harmonize several instruments to create music of a finer quality and of greater harmony.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:—

1. A base bar for a violin, in combination with the upper wall of a violin, of a base bar secured by its ends to the underside of said wall, and having that portion thereof intermediate its ends spaced apart therefrom, a secondary bar mounted to the under surface of said upper wall and spaced apart from said base bar, and a tension bar slidably positioned between said base bar and said secondary bar.

2. A base bar for a violin, in combination with the upper wall of a violin, of an arched base bar, longitudinally semicircular in cross section mounted to the underside of said upper wall, and having that portion intermediate its ends spaced from said upper wall; a secondary bar mounted to the underside of said top wall and in a vertical plane with said base bar, said secondary bar having an unattached edge longitudinally semicircular in cross section and spaced between said base bar and top wall; and a grooved tension bar disposed between and slidably engaging said base bar and said secondary bar.

MICHAEL REDLINGER.
